CHRISTMAS GIFT BOX

George Borkin, Belle Harbor, N.Y., assignor to Bulova Watch Company, Inc., Flushing, N.Y., a corporation of New York

Application October 17, 1958, Serial No. 53,018

Term of patent 7 years

(Cl. D58—11)

Fig. 1 is a perspective view of the Christmas gift box of my new design.

Fig. 2 is a side view of the Christmas gift box.

Fig. 3 is a side view similar to Fig. 2 but from the opposite side and showing the box with the panel open.

The rear of the disk at the top of the box not shown is the same as the front shown.

I claim:

The ornamental design for a Christmas gift box, substantially as shown and described.
